UNITED STATES PATENT OFFICE.

GEORGE A. FLACCUS, OF WHEELING, WEST VIRGINIA.

DESIGN FOR A BOTTLE.

SPECIFICATION forming part of Design No. 29,331, dated September 13, 1898.

Application filed August 15, 1898. Serial No. 688,650. Term of patent 7 years.

To all whom it may concern:

Be it known that I, GEORGE A. FLACCUS, a citizen of the United States, residing at Wheeling, in the county of Ohio and State of West Virginia, have invented and produced a new and original Design for Bottles; and I do hereby declare the following to be a full, clear, and exact description of the same, reference being had to the accompanying drawing, forming a part thereof.

The accompanying drawing is a perspective view of a bottle embodying my design.

The leading feature of my design consists of a bottle which is shaped to represent a figure of the type usually known as "Uncle Sam," the same being represented as standing in an upright position on a pedestal and wearing a hat which forms the mouth of the bottle.

In the accompanying drawing, A represents the figure of a man of the type usually known as "Uncle Sam." The figure is represented as standing in an upright position on a pedes-

tal B, which forms the base of the bottle, with one hand resting upon a gun C, and wearing 25 a hat D, which latter forms the mouth of the bottle, the mouth of the bottle being closed by a capsule, which gives an added finished appearance to the hat. The figure has long back hair D and whiskers E. The figure is 30 represented as having a long-tail coat F, with stars upon the same, and wearing a piccadilly-collar and a string tie. The trousers of the figure are represented as being striped.

Having now described my invention, what 35 I claim as new, and desire to secure by Letters Patent, is—

The design for a bottle, substantially as herein shown and described.

In testimony whereof I hereunto affix my 40 signature in presence of two witnesses.

GEORGE A. FLACCUS.
